DESIGN FOR A WORKTABLE

Harold B. Maynard, Pittsburgh, and Charles W. Punton, Wilkinsburg, Pa., assignors to Methods Development and Equipment Company, Wilkinsburg, Pa., a partnership

Application August 30, 1944, Serial No. 115,144

Term of patent 14 years

(Cl. D33—14)

To all whom it may concern:

Be it known that we, Harold B. Maynard and Charles W. Punton, citizens of the United States, residing, respectively, at Pittsburgh, and R. D. 1, Wilkinsburg, both in the county of Allegheny and State of Pennsylvania, have invented a new, original, and ornamental Design for a Worktable, of which the following is a specification, reference being had to the accompanying drawing, forming part thereof,

In the drawing:

Fig. 1 is a front elevational view of a worktable showing our new design; and

Fig. 2 is a perspective view thereof as it appears with the top in elevated position.

We claim:

The ornamental design for a worktable, as shown.

HAROLD B. MAYNARD.
CHARLES W. PUNTON.
